(57) **CLAIM**

The ornamental design for a fishing skirt tool, as shown and described.

DESCRIPTION

FIG. 1 is a perspective view of a fishing skirt tool, showing my new design;

FIG. 2 is a front view thereof;

FIG. 3 is a rear thereof;

FIG. 4 is a bottom view thereof;

FIG. 5 is a top view thereof;

FIG. 6 is a left thereof; and,

FIG. 7 is a right view thereof.

The broken lines shown in the drawings depict portions of the beverage capsule that form no part of the claimed design. The shading is provided to illustrate contour and material type only and is not an indication of texture, gloss, etc.
